UNITED STATES PATENT OFFICE.

WILLIAM W. CAMERON, OF LA CROSSE, WISCONSIN, ASSIGNOR TO LA CROSSE PLOW CO., OF LA CROSSE, WISCONSIN, A CORPORATION OF WISCONSIN.

PLOW.

1,227,745.

Specification of Letters Patent. Patented May 29, 1917.

Application filed September 25, 1913. Serial No. 791,708.

To all whom it may concern:

Be it known that I, WILLIAM W. CAMERON, a resident of La Crosse, in the county of La Crosse and State of Wisconsin, have invented certain new and useful Improvements in Plows, of which the following is a full, clear, and exact description.

The invention relates to plows and more particularly to tractor-plows embodying a mechanism for raising the plows by power.

In tractor-plows, it is customary to provide separate lifting-mechanism for each plowshare of a gang, and mechanism for successively operating them to cause the plow bodies, arranged in a diagonal line for successive operation, to enter and leave the ground substantially on a transverse line, and it is desirable to separately regulate the depth of the cut of each plow. It is also desirable to avoid the use of a long swinging lever in a tractor-plow.

An object of the invention is to provide improved depth regulating mechanism for the individual plows which may be operated while the machine is in operation, and which avoids the use of a long lever for effecting this adjustment.

A further object of the invention is to provide improved means for rendering any one of a gang of plows inoperative by the power-operated lifting or lowering mechanism, so that the machine may be operated without one or more of the plows.

A further object of the invention is to provide improved power-operated lifting mechanism.

A further object of the invention is to provide improved means for manually operating the lifting-mechanism and which dispenses with the necessity of providing a lever which will be swung by the power-operated lifting mechanism.

Other objects of the invention will be apparent from the description of the plow hereinafter set forth.

The invention consists in the several novel features hereinafter set forth and more particularly defined by claims at the conclusion hereof.

In the drawings; Figure 1 is a plan of a portion of a plow embodying the invention. Fig. 2 is a section taken on line 2-2 of Fig. 1, the plowshare being shown in raised position. Fig. 3 is a vertical transverse section taken on line 3-3 of Fig. 2.

Fig. 4 is a detail of the power-operated lifting-mechanism, showing it in the position assumed by the parts when the plowshare has been raised by the power-operated lifting-mechanism, in which position the lifting linkage has passed the dead center, so it will be automatically locked to hold the plowshare raised. Fig. 4^a is a view showing the lifting-dog in position assumed when the parts are in position shown in Fig. 4. 60 Fig. 5 is a detail view showing the lifting-mechanism in the position assumed by the parts when the lifting-linkage has been rendered inoperative by the power-operated lifting and lowering mechanism, so that one plow will be locked and inoperative by the power-operated mechanism, while the others may remain operative by said mechanism. Fig. 5^a is a view showing the lifting-dog in position assumed when the mechanism is in the position shown in Fig. 5. 70 Fig. 6 is a detail of the lifting-mechanism showing the parts in position assumed when the plow has been lowered. Fig. 7 is a section taken on line 7-7 of Fig. 1, showing the clutch for operating the plow-operating shaft and the controlling device therefor. Fig. 8 is a front elevation of one of the plow-shifting mechanisms. Fig. 9 is a detail section of the sliding stop on the operating link of one of the plow-shifting mechanisms, being a section taken on line 9-9 of Fig. 5. Fig. 10 is a section taken on line 10-10 of Fig. 6. Fig. 11 is a perspective of the sliding lock on the lifting 80 mechanism. Fig. 12 is a plan of one of the plow shifting mechanisms. Fig. 13 is a detail of the section of the dog of the clutch for operating the plow-operating shaft and the controlling device therefor. Fig. 14 is a section taken on line 14-14 of Fig. 13. 85

The improved plow comprises a suitable frame which may be sustained by carrying-wheels, as well understood in the art and by a traction-wheel 22, which is mounted on 100 and drives an axl 23, which is journaled in bearings rigid on the frame. The latter comprises a front rail 15, a side rail 16, and a diagonal bar 17. The plow may be connected to the tractor by any suitable means, 105 as well understood in the art.

The plow comprises a series of plow-beams 27 arranged in diagonal succession to operate successively in the ground. A plow-share 28 is suitably connected to each beam 110

27. The front of each beam 27 is pivotally connected, as at 29 to a coupling 30 secured to the rail 17, to permit the rear end of the beam and the plow carried thereby, to be raised or lowered. A gage wheel 33 is provided for each plowbeam and carries a fork 34 on the lower end of a standard 35 which is slidably held in a bracket 35^a secured to said beam. A bell-crank lever 38 is pivoted to the beam, as at 38^a and a link 36 connects one arm of said lever to the standard 35.

16 The plow-shifting-mechanism for each beam comprises a link 40, which is pivoted, as at 39, to one of the arms of bell-crank lever 38. Each link 40 has its front end curved downwardly and pivoted as at 42 to an arm 43 which is pivoted on a power-driven shaft 44 which is journaled in suitable brackets 18 on the frame. The pivotal connections of arm 43, link 40 and lever 38 are relatively disposed to permit the linkage to pass across dead center relation and cause the plow beam to be automatically locked or held in raised position, as shown in Fig. 4.

25 An improved depth-regulating device is provided for each plow-beam, and each of these devices comprises a link 45, which has its front end pivotally connected, as at 47 to arm 43, and its rear end pivoted, as at 52 to a slide 53 on link 40. The upper portion 30 of slide 53 is extended to form an abutment 54 adapted to engage a screw 49, which has a screw-threaded connection with a bracket 50, which is secured to link 40. The front 35 end of screw 49 is bent to form a crank 51 whereby the screw may be turned to adjust its rear end, which engages the slide 53. Link 45, being pivotally connected to the power-operated arm 43 and eccentrically 40 with respect to the fulcrum of the arm and with respect to pivot 42 between link 40 and arm 43, will be differentially operated relatively to link 40 during shift of one of the plow-shifting mechanisms. When the 45 link 40 is in position shown in Fig. 6, and the plow-beam is lowered, link 45 will serve to limit the movement of link 40 through slide 53 and thus serve to limit the depth of the cut of the plow. By adjusting screw 49, 50 the point at which link 40 will be arrested may be varied to permit the plow to travel deeper or to hold it higher in the soil. Links 40 and 45 are both differentially operated by the lifting-arm 43, so that when stop 55 screw 49 is arrested, slide 53 will lock the entire linkage against movement in one direction. By providing an adjusting screw on each of the links 40, the use of long levers is avoided, and the crank 51, by which 60 the screw may be adjusted, may be conveniently and readily operated from the platform on which the operator usually stands while the machine is at work. For strength, each link 45 comprises dual members at the 65 sides of arm 43 and link 40, respectively.

In tractor plows, occasion sometimes arises when it is desired to raise or lower one of the plows of the gang without shifting the others, and for this purpose, a long lever is usually provided. In tractor-plows in 70 which a number of levers are necessary for this purpose, it is desirable to dispense with such levers, particularly if they are operated by power-lifting mechanism, because the quick shift of such levers sometimes causes 75 an injury to the operator. The present invention provides means for manually operating any of the plow-shifting-mechanisms individually without the use of a power-operated long lever whereby the operator 80 might be injured. For this purpose, a socket 43^a is formed on each arm 43 and is adapted to receive one end of a bar or round 85 of metal 43^b, as shown in Fig. 6. In practice, this bar is carried at some convenient place 90 on the plow or tractor and whenever it becomes necessary to raise one of the plows manually, the operator will insert the bar 43^b into the socket 43^a of the arm 43 of the lifting-mechanism for the plow to be raised, 95 and easily operate said mechanism. Then the bar may be readily removed and the front portion of the plow will be entirely free from any long swinging levers which the operator must avoid if he is observing 100 the operation of the plows from the tractor or the front of the plow.

The depth-regulating device, hereinbefore described, permits each plow-shifting linkage to be operated by the power or manually, 105 independently of the others.

A ratchet wheel 55 is fixed on shaft 23 and is constantly driven by the traction-wheel 22. A controllable driving-connection between the wheel 57 and the plow-operating shaft 105 44 comprises a sprocket-chain 56, a sprocket-wheel 57, which is loose on the shaft 23 and a sprocket-wheel 58 fixed on shaft 44. Sprockets 57 and 58 have the same number of teeth so that they will be driven at the 110 same relative speed. An automatically releasable clutch for driving shaft 44 comprises an arm 59 on or rigid with sprocket 57 and a dog 60 pivoted as at 61 to the outer end of said arm. Normally, the dog is disposed above the ratchet, so it will fall into engagement therewith when it is released. An abutment 63 is pivoted to said dog, as at 63^a and pressed away from the end of the dog by a spring 63^b. The movement of the 120 dog by the spring is limited by a suitable stop 63^c. A controller rod 64 is adapted to be moved into the path of dog 60 to arrest the dog after one complete revolution of the clutch and to automatically disengage the 125 dog from the ratchet. A fixed guide 62 serves to hold the dog in engagement with the ratchet during a portion of each revolution of the dog. Controller rod 64 is slidably mounted in guides 65 of the frame and 130

a spring 66 serves to normally press the rear end of said rod into the path of abutment 63. The front end of rod 64 is pivoted to a controller-lever 67 which is adapted to be operated by a cable or rod 67^a extending forwardly to the tractor. When lever 67 is moved forwardly, rod 64 will be withdrawn from the path of abutment 63, the dog will then pass into engagement with ratchet 55 and the clutch will be driven one complete revolution at the end of which, abutment 63 will be arrested by controller-rod 64 to disconnect the dog from the ratchet. After such disengagement, spring 63^b will then shift the dog away from ratchet to entirely clear it. Resultantly, each time lever 67 is operated, the clutch will drive chain 56 to drive the plow-operating shaft 44 one complete revolution, at the end of which the clutch will be automatically thrown out of action.

A dog 69 is pivoted to each arm 43, as at 70 and said arm is preferably formed of dual members between which the dog is confined. Between the hubs of the arm-members, a collar 72 which is provided with a tooth 73 is fixed on shaft 44 to engage dog 69 and shift arm 43 to lift the plow-beam by power derived from the traction-wheel. When the plow-beam is lowered, (Fig. 6), the end 69^a of dog 69 is disposed in the path of rotation of tooth 73. A tappet 74 on one side of collar 72 is adapted to engage a lug 75 formed on bracket 50 in which screw 49 is held and which is secured to link 40. This tappet, in its rotation with shaft 44 and collar 72 serves to lift the link a short distance to cause the plow-shifting linkage to cross its dead-center and unlock or release it, so that the weight of the plow-beams will be applied to lower the plows into the ground. Tooth 73 serves to engage the end of dog 69 and to shift the arm 43 and its plow-shifting linkage to raise the plow-beam. The tappet serves as power-operated means for moving arm 43 to shift the linkage across its dead-center, so that the plow and beam will be released to fall by gravity. A stud 69^b on dog 69 projects laterally therefrom and an accurate guide *a* formed on a stationary part, such as the bearings 18 for the shaft 44, serves to engage said stud to hold the dog out of operative relation with tooth 73 during a lowering operation, so that the dog will not fall into the path of said tooth until the plow-beam has been fully lowered. The inner face of this guide *a* will, by arresting stud 69^b against outward movement, prevent accidental disengagement of dog 69 and tooth 73 during a lifting-operation. A link 40 and arm 43 is provided for each beam and constitute a lifting connection therefor. Each connection is operable by hand independently of the others.

Assuming the plow-shifting mechanism

for a beam to be in position shown in Fig. 4, with the plow raised, the latter will be held raised by the self-locking or dead-center relation of the lifting-linkage. When it is desired to lower the plows, lever 67 will be pulled forwardly to permit the clutch 55, 59, 60 to become operative and cause it to drive shaft 44 one complete revolution during which lug 74 will engage lug 75 to lift the front end of link 40 above the dead-center, and arm 43 will be swung upwardly thereby sufficiently to cause the weight of the beam and plow to drop, the lifting-linkage being free to permit this movement when it crosses its dead-center.

When the plows are in the ground, the shifting-linkage will be in position shown in Fig. 6. If it is desired to raise them, the operator will again pull lever 67 forward to render the clutch 55, 60 operative for one complete revolution and during this movement, each linkage will be operated by its tooth 73 to catch dog 69 and swing its arm 43 forwardly to operate link 40 and raise the plow. The tail of said dog is formed so it will be struck by the curved end of the link 40 to disengage it from tooth 73 after the linkage has passed its dead-center, so that it will be automatically held in position to hold the plow and beam raised.

It sometimes occurs that it is desired to keep one or more of the plows raised and to leave the other plows operative by the power-shifting mechanism. The invention provides means for rendering any of the plows inoperative by the power-operated lifting-mechanism, so that the plows to be used will remain operable by the power-operated mechanisms. For this purpose, a pin 80 is slidably held in slide 53 and is provided with a terminal 81 which is adapted to pass through an aperture 82^a in slide 53 and into aperture 82 in link 40 to lock links 45 and 40 against relative movement. Spring 83 normally presses the pin, so that its terminal 81 will be held in aperture 82 and permits it to be withdrawn therefrom and swung laterally in a groove 84 in one side of slide 53 whereby the pin will be held inoperative and out of engagement with link 40. When this locking pin is in operative position to lock linkage against operation by the power-mechanism, the parts will be in position shown in Fig. 5. When pin-terminal 81 is swung into aperture 82^a while the lifting connection is in position shown in Fig. 4, it will engage the side link 40 and will spring into aperture 82 of the link 40, as the linkage passes from the position shown in Fig. 4 at which time the linkage will be automatically locked in raised position, to the position shown in Fig. 5, at which time the linkage will be unlocked against movement by the beam. Resultantly, if a terminal 81 of pin 80 is turned

to pass through the hole 82^a in link 40, when the plow has been raised by power, the next rotation of shaft 44 will cause tappet 74 to strike abutment 75 and raise the latter sufficiently to shift the linkage across the dead center, so that the weight of the beam will be applied to operate link 40 rearwardly and then, before the plows have been lowered sufficiently to enter the ground, and 5 pin-terminal 81 which will spring into aperture 82 as the linkage reaches the position shown in Fig. 5, will lock links 45 and 40 together against relative movement and serve to hold the plow-beam raised. When 10 the parts are in the position shown in Fig. 5, abutments 75 will be out of the path of tappet 74 and dog 69 will be out of the path of tooth 73. Resultantly the remaining lifting-mechanisms may be operated by 15 power, while the one which has been locked by its pin 80 will hold the plow inoperative. This mechanism thus exemplifies a device by 20 which any of the lifting-mechanisms may be locked to hold the plow raised, while the remaining lifting-mechanisms will remain operative by power.

For the purpose of causing the plows to be successively raised, the teeth 73 for the 25 several shifting-mechanisms, are set in rotative succession on shaft 44 and for the purpose of successively releasing the mechanisms, tappets 74 are also placed in rotative succession on said shaft. Resultantly, during alternate revolutions, said shaft will 30 alternately and successively operate the shifting-mechanisms to raise and lower the plows.

The invention is not to be understood as 35 restricted to the details set forth, since these 40 may be modified within the scope of the appended claims, without departing from the spirit and scope of the invention.

Having thus described the invention, what I claim as new and desire to secure by 45 Letters Patent, is:

1. In a plow, the combination with a frame, carrying wheels and a plow beam, of a power operated lift connection for the beam, a depth regulating device comprising 50 coöperating members whereby the lowering movement of the connection will be limited, both of said members being mounted on and shifted by said connection in lowering the beam, and means for locking one 55 of the members of the regulating device to the lifting connection to hold the plow on the beam out of the ground.

2. In a plow, the combination with a frame, carrying-wheels, and a plow-beam, 60 of a power-operated lifting-connection, a depth-regulating device comprising co-operating members for limiting the movement of the connection in lowering the beam, means for locking one of said members of the regulating-device to the shift-

ing-mechanism to hold the plow raised, and a shaft provided with means for operating said connection, the shaft and means thereon being rotatable without operating the connection when the regulating-device is 70 locked to said connection.

3. In a plow, the combination with a frame, carrying-wheels, and a plow-beam, of a power-operated lifting-connection, a depth-regulating device comprising coöperating members for limiting the movement of the connection in lowering the beam comprising two stop-members, means for locking one of said members of the regulating device to the shifting-mechanism to hold 75 the plow raised, and a shaft provided with means for operating said connection, said shaft being rotatable without operating the connection when the regulating-device is 80 locked to said connection.

4. In a plow, the combination with a frame, carrying wheels and a plow beam, of a lifting connection comprising a link, power operated mechanism for operating said connection and a depth regulating device comprising a link, an adjustable stop screw mounted on one of said links and a coöperating member connected to the other of said links, said screw being adjustable by rotation to vary the movement of the 95 connection.

5. In a plow, the combination with a frame, carrying-wheels, and a plow-beam, of a power-operated lifting-connection comprising a link, a depth-regulating device 100 comprising a link and two stop-members on the links respectively, and a screw for adjusting the movement of the connection.

6. In a plow, the combination with a frame, carrying-wheels, and a plow-beam of a power-operated lifting-connection comprising a link, a depth-regulating-device comprising a link and said connection respectively, one of said members comprising 110 a screw on the connection-link for varying the movement of the connection.

7. In a plow, the combination with a frame, carrying-wheels and a plow-beam, of a power-operated lifting-connection comprising a link, a depth-regulating device 115 comprising a link and two separable stop-members on the links respectively, and a screw on the connection-link for varying the movement of the connection.

8. In a plow, the combination with a frame, and a plow beam, of a lifting connection comprising link and an arm, power operated mechanism for operating said connection comprising a shaft on which said arm is pivoted, a stop member supported 125 by and slideable on the link and a coöperating member on the link, one of said members being adjustable relatively to the link to vary the depth of the cut.

9. In a plow, the combination with a 130

frame, and a plow beam, of a lifting connection comprising a link and an arm, power operated mechanism for operating said connection comprising a shaft on which said arm is pivoted, a stop member supported by and slidable on the link and an adjustable stop screw coöoperating with said slidable member to vary the depth of the cut, mounted on and supported by the link.

10. In a plow, the combination with a frame, and a plow-beam, of power-operated lifting-connection, comprising a link, a device for limiting the movement of the link in lowering the beam, comprising a link and a slide and an adjustable stop between the slide and the connection-link to vary the depth of the cut.

11. In a plow, the combination with a frame, carrying-wheels and a plow beam, of a lifting connection comprising a link and an arm, power operated mechanism comprising a shaft on which the arm is pivoted, a depth regulating link pivoted to said arm and means for locking the regulating link to the link of the lifting connection.

12. In a plow, the combination with a frame, carrying-wheels and a plow-beam, of a power-operated shifting-connection comprising a link, depth-regulating means comprising a link pivoted to said shifting-mechanism and an adjustable stop-device between the links.

13. In a plow, the combination with a frame, carrying-wheels and a plow-beam, of a power-operated shifting-connection comprising a link and a depth-regulating mechanism comprising a link, and means on the connection for operating the regulating link differentially with respect to the shifting-link.

14. In a plow, the combination with a frame, carrying-wheels, and a plow-beam, of a power-operated shifting-connection, comprising a link, depth-regulating mechanism comprising a link, means on the connection for operating the regulating-link differentially with respect to the shifting-link and an adjustable stop-device between the links.

15. In a plow, the combination with a frame, carrying-wheels, and a plow-beam, of power-operated shifting-mechanism, comprising a link, depth-regulating mechanism comprising a link, means for operating the regulating link by said connection differentially with respect to the shifting-link, and means for locking the links together to hold the beam raised.

16. In a plow, the combination with a frame, carrying-wheels and a plow-beam, of a power-operated shifting-connection comprising a link, depth regulating-mechanism comprising a link, means on the connection for operating the regulating link

differentially with respect to the shifting-link, an adjustable stop-device between the links, and means for locking the links in position to hold the beam raised.

17. In a plow, the combination with a frame, carrying-wheels and a plow-beam, of a power-operated shifting connection comprising a link, depth regulating mechanism comprising an adjustable screw mounted on the link, a stop-member slidably connected to the link, and a link pivoted to said slideable stop-member.

18. In a plow, the combination of a frame, carrying-wheels and a plow-beam, of a power-operated shifting connection comprising a link, depth-regulating mechanism comprising a screw mounted on the link, a stop-member slidably connected to the link, a link pivoted to said member and means for locking said member to the link.

19. In a plow, the combination with a frame, carrying wheels and a plow beam, of a lifting linkage, power operated means for operating the linkage comprising a shaft, and means on the linkage to which a lever may be detachably connected to operate it manually, said linkage being operable by the lever independently of said shaft.

20. In a plow, the combination with a frame, carrying wheels and a series of plow beams, of separably operable lifting linkages for the beams, power operated mechanism for operating said linkages, comprising a shaft, means on each linkage to which a lever may be detachably connected and a lever adapted to be connected to either of the linkages to operate them separately, said linkages being operable by said lever independently of the shaft.

21. In a plow, the combination with a frame, carrying wheels and a plow beam, of a lifting linkage, power operated mechanism for operating the linkage comprising a shaft and a socket in said linkage adapted to receive a removable lever for manually operating the linkage, the latter being operable by said lever independently of the shaft.

22. In a plow, the combination with a frame, carrying wheels and a series of plow beams, of separately operable lifting linkages for the beams, power operated mechanism for operating said linkages and a socket on each of the linkages adapted to receive a removable lever for manually operating any of said linkages, said linkages being operable by the lever independently of said mechanism.

23. In a plow, the combination with a frame, carrying-wheels and a plow-beam, of a power-operated shaft, an arm on said shaft, a connection between the beam and the arm comprising a link connected to said arm, means between the shaft and the arm for operating the arm and means on the arm adapted to receive and removably hold a

lever whereby the link may be manually operated, said arm being operable by the levers independently of the shaft.

24. In a plow, the combination with a frame, carrying-wheels and a plow-beam, of a power-operated shaft, an arm on said shaft, a connection between the beam and the arm comprising a link connected to said arm, means between the shaft and the arm for operating the arm, and a socket on the arm adapted to receive and removably hold a lever whereby the link may be manually operated, said arm being operable by the lever independently of the shaft.

25. In a plow, the combination with a frame, carrying-wheels and a series of plow-beams, of a power-operated shaft, a series of arms on said shaft, connections between the beams and the arms, each comprising a link connected to one of said arms, means between the shaft and the arm for operating the arm, and means on each of the arms adapted to receive and removably hold a lever whereby the link may be manually operated, said arm being operable by the lever independently of the shaft.

26. In a plow, the combination with a frame, carrying-wheels, and a plow-beam, of a power-operated shaft, an arm on said shaft, a dog on said arm, means on the shaft for engaging the dog to operate the arm, a connection between the beam and said arm comprising a link and a fixed guide for holding the dog out of engagement with the means on the shaft and means for disengaging the dog from the means on the shaft.

27. In a plow, the combination with a frame, carrying-wheels, and a plow-beam, of a power-operated shaft, an arm on said shaft, a dog on said arm, means on the shaft for engaging the dog to operate the arm, a connection between the beam and said arm comprising a link and a fixed guide for holding the dog out of engagement with the means on the shaft, and means on the link for disengaging the dog from the means on the shaft.
